UNITED STATES PATENT OFFICE.

WILLIAM MORRISON BLACK, OF BOSTON, PENNSYLVANIA.

RAILWAY TIE.

Application filed September 8, 1927. Serial No. 218,217.

This invention relates to new and useful improvements in railway ties and aims to provide a tie that is so constructed as to permit the rails to be anchored thereto without necessitating the use of spikes or other driven fasteners.

In carrying out the present invention, there is provided a tie constructed of parts of molded metal cooperating with which 10 are readily attachable and detachable means for anchoring the rails thereto.

One of the most important objects of the invention is to provide a tie wherein the life 15 of the same is practically indefinite and wherein the rails may be quickly anchored to or removed therefrom.

With the foregoing and other objects in view as the nature of the invention will be better understood, the same comprises the 20 novel form, combination and arrangement of parts hereinafter more fully described, shown in the accompanying drawings and claimed.

Figure 1 is a top plan of my improved tie, 25 a pair of rails being fragmentarily disclosed as disposed thereon,

Figure 2 is a side elevation,

Figure 3 is an enlarged horizontal section taken substantially on the line 3—3 of Figure 1 for more clearly disclosing the means whereby the rails are secured to the ties, and,

Figure 4 is a perspective of one of the locking keys employed in carrying out the 35 present invention.

Now having particular reference to the drawings, 5 designates a tie of cast or molded metal and of predetermined length and width. The top surface of this tie is formed 40 adjacent its opposite ends with transversely extending channels 6—6 of very minor depth within which the base plates a—a of a pair of rails A—A are disposed. Extending parallel with these rail base receiving channels 45 6—6 and of relatively greater depth than said channels 6—6 are dove-tailed channels 7—7. Furthermore, the top surface of the tie is provided with still further channels 8 that bi-sect each dove-tailed channel 7 intermediate the ends thereof.

The invention further consists of means 50 for securing each rail A in a position within its channel 6 said means consisting of a pair of relatively Z shaped heavy metallic cleats 55 9—9 the upper legs of which are slightly inclined for engagement over the inclined

top surface of the base of the rail on opposite sides of the top portion thereof. The lower legs of these cleats are plane and are adapted to rest within the horizontal channels 8—8 and upon the bottom walls thereof as clearly disclosed in Figure 3. The outer surfaces of the web portions of these cleats are beveled to conform to the sides of the dove-tailed transversely extending channels 60 7—7. After these cleats have been disposed in the position as indicated in Figure 3, dove-tail locking keys 10—10 are forcibly 65 driven within the transverse channels 7—7 for obviously binding against the web portions of the cleats 9—9 to prevent the disengagement of the same from the tie and rail.

It will thus be seen that I have provided a highly novel, simple and highly efficient 70 railway tie together with means for facilitating the anchoring of the rails thereto, and even though I have herein shown and described the invention as consisting of certain detailed structural elements, it is nevertheless 75 to be understood that some changes may be made therein without affecting the spirit or scope of the appended claims.

I claim:

1. In a rail tie of the character described, 80 a metallic body for disposition transversely beneath a pair of spaced rails, the top surface of the tie beneath each rail being formed with a shallow transverse channel for receiving the base of the rail, the top 85 surface of the body being formed with deep channels at the sides of the first-mentioned channels which latter mentioned channels are intersected by other channels, a pair of elongated relatively Z-shaped cleats for each 90 rail the upper legs of which are adapted for engagement upon the rail base and the lower legs for engagement within the longitudinal channels and key members for engagement 95 within the deep channels for binding the 100 lower legs of the cleats therein.

2. In a rail tie of the character described, 105 a metallic body for disposition transversely beneath a pair of spaced rails, the top surface of the tie beneath each rail being formed with a shallow transverse channel for receiving the base of the rail, the top surface 110 of the body being formed with deep channels at the sides of the first-mentioned channels which latter mentioned channels are intersected by other channels, a pair of elongated relatively Z-shaped cleats for each rail

the upper legs of which are adapted for engagement upon the rail base and the lower legs for engagement within the longitudinal channels, and key members for engagement 5 within the deep channels for binding the lower legs of the cleats therein, said deep channels in the body being dove-tailed while

the outer face of the connecting portion of each cleat is beveled in conformity to the bevel of the key members whereupon the members and cleats are prevented from vertical movement within the deep channels.

In testimony whereof I affix my signature.

WILLIAM MORRISON BLACK.
